LATCH MECHANISM

Sidney B. Whittier, Barnstable, Mass.

Application November 26, 1938, Serial No. 242,452

5 Claims. (Cl. 292—153)

This invention relates to improvements in latch mechanism for automobile doors and more particularly to latch mechanism which may be operated by an external handle or an internal handle, the internal handle being also operable to secure the bolt in projected position.

It is an object of the invention to provide a latch mechanism of the kind described which is contained in a relatively flat housing offset from the axis of the bolt so as not to interfere with the sheet of glass which is used as a window for an automobile door and which is mounted to be lowered into the body of the door from the window opening.

Another object of the invention is to provide latching mechanism which is easy to open and easy to shut, so that slamming is unnecessary and muscular effort of the operator is reduced to a minimum.

It is a further object of the invention to provide a latch mechanism in which the bolt is positively held in its retracted position and in its projected position until released by suitable means.

It is a further object of the invention to provide a bolt with a conical or tapering end fitting into a lined socket in the door jamb and positively held therein while the door is shut so as to prevent relative working between the door and the door frame.

Other advantageous features will be apparent to one skilled in the art from the description of certain embodiments of the invention which follows and from the drawings of which—

Figure 1 is a perspective view of a fragmentary portion of an automobile including a door in which is mounted mechanism embodying the invention.

Figure 2 is a side elevation of a latching mechanism, the side plate of the housing being omitted to show the working parts.

Figure 3 is a view similar to Figure 2 but showing a portion of the door jamb and showing the working parts in different positions of operation.

Figure 4 is similar to Figure 2 but showing some of the parts in different positions of operation.

Figure 5 is a section on the line 5—5 of Figure 3.

Figure 6 is a section on the line 6—6 of Figure 3.

Figure 7 is a fragmentary elevation similar to Figure 2 but showing the parts in different positions of operation.

Figure 8 is a side elevation of a modified form of the invention.

Figure 9 is a section on the line 9—9 of Figure 8.

Figure 10 is a section on the line 10—10 of Figure 8.

Figure 11 is a section on the line 11—11 of Figure 8.

Figure 12 is a side elevation of another modified form of the invention.

Figure 13 is a section on the line 13—13 of Figure 12.

Figure 14 is a section on the line 14—14 of Figure 12.

Referring to the drawings, Figure 1 is a fragmentary view of an automobile body including a door 20 having a latching mechanism 22 mounted therein with an exterior handle 24 and an interior handle 26. The latching mechanism, as indicated in Figure 2, includes a bolt 30 which is horizontally slidable in the casing of the lock and is provided with a tapering head 32 adapted to project through an opening 34 in the edge of the door into a socket 36 in the door jamb 38. As shown in Figure 3, the socket 36 is preferably lined as at 40 with a rubber lining, the bolt head 32 fitting snugly in the lining 40. The tapering extremity of the bolt head 32 may be frusto-conical, as shown, or may be conical or rounded as desired, but in any event the tapered end portion is preferably followed by a cylindrical portion 42 which merges into the conically tapered portion and fits snugly into a cylindrical portion of the socket 36. In order to make room for the window glass carried by the door, the bolt head 32 is relatively short, the shank portion of the bolt being shown as a pair of plates 44 and 46 which are secured to each other face to face, both plates being secured to the bolt head 30. The two plates 44 and 46 and the bolt head 30 may all be cast as an integral unit if preferred, the plates 44 and 46 being laterally offset from the axis of the bolt head so as to slide between the side walls 50 and 52 which, with the front wall 54, form a housing having a thickness less than half the width of the front wall.

The operating mechanism is located in said housing and comprises a tumbler 56 in the form of a bell-crank which is preferably made of plate of the same thickness as the plate 44. This tumbler is pivotally mounted on the bolt. To this end, it may be provided with a circular portion 58 which fits in a socket 60 formed by a circular recess in a side edge of the plate 44. This tumbler 56 also includes an arm 62 the end of which engages a shoulder 64 on a stationary plate 66. The tumbler 56 also has an upright arm 70 which is engageable by an arm 72 of a roll-back

45 50 55 60 65 70 75 80 85 90 95

14 which is mounted on a squared rockshaft 76 to which the outer door handle 24 is secured. When the rockshaft 76 is rocked in a counter-clockwise direction, as shown in Figures 2 and 3, the arm 72 bears against the arm 70 and rocks the tumbler 56 so that the arm 62 moves clear of the shoulder 64, whereupon the bolt is free to be retracted. Further movement of the arm 72 pushes the tumbler 56 toward the right, this resulting in retractive movement of the bolt owing to the engagement of the portion 58 of the tumbler 56 in the circular socket 60. This movement of the tumbler 56 and the bolt is against the pressure of a spring 75 which bears against the arm 70. This spring tends to project the bolt toward the left but need not be particularly strong since the bolt is normally locked in its projected position by the engagement of the arm 62 against the shoulder 64. Thus the spring 75 is relieved of the function of holding the bolt in projected position. A spring 78 bears against a finger 80 on the roll-back 14 so as to tend to rotate the shaft 76 in a clockwise direction to the normal position of the shaft shown in Figure 3.

The bolt 30 may also be operated by manipulation of the interior handle 26. To this end, the handle is connected by a suitable bar 82 to a plate 84 which is slideable in the housing. This plate is provided with an elongated horizontal slot 86 to receive a lug 88 which is struck down from the arm 70 and projects into the slot 86 as indicated in Figure 5. For this purpose the plate 84 is mounted above and in a common plane with the plate 46. When the bolt is operated by the outer handle 24, the lug 88 travels idly in the slot 86, the plate 84 remaining stationary. If the interior handle 26 is operated to retract the bolt, the left-hand end of the edge of the slot 86 engages the lug 88 as the plate 84 is moved toward the right. This rocks the tumbler 56 toward the right, as previously described, releasing and retracting the bolt 30. The interior handle 24 may be operated in the opposite direction to lock the bolt in such a manner as to render the outer handle 24 inoperative. For this purpose a nose 90 is provided on the left-hand end of the plate 84, this nose being movable into engagement with a shoulder 92 on the roll-back 14 when the plate 84 is moved to the left from the position shown in Figure 2 to the position shown in Figure 7. This locking movement of the plate 84 is against the resistance of a spring-pressed detent 94 which is engaged by a projection 96 on the upper edge of the plate 84. The detent 94 prevents movement of the plate 84 into its locking position unless positively moved to such position by operation of the interior handle 26. A suitable spring 96 is provided to press against a lug 98 on the plate 84 so as to press the plate 84 toward the left. This spring, however, is of insufficient strength to move the plate to the locking position shown in Figure 7.

Another tumbler is provided to hold the bolt in its retracted position. This consists of a dog 100 which has a trigger portion 102 projecting through the end wall 54 of the casing. The tumbler is rockable to and from a position in which the inner end 103 of the dog engages a shoulder 104 on the plate 44. A lug 105 on the tumbler is seated in a slot in the wall 50 to act as a fulcrum for the tumbler. The dog 100 is yieldingly held in locking position by a suitable spring 106, as indicated in Figure 6. When the door is swung shut, the trigger element 102 engages a tripping device which may be a setscrew

108 adjustably mounted in the door jamb, the projecting end of this setscrew being in the path of the trigger member 102. This engagement rocks the dog 100 to the position shown in Figure 6, releasing the plate 44 so that the bolt 30 is free to move toward the left under the influence of the spring 75. The screw 108 is adjusted so that the bolt is released just as it reaches a position opposite the socket 36. The spring 75 thereupon moves the bolt toward the left so that the bolt head 30 enters the socket. The spring also rocks the lever member 56 so that the arm 62 engages the shoulder 64 and positively locks the bolt against retractive movement until the tumbler 56 has been rocked by the exterior or interior door handle. As shown in Figure 6, the cam face of the trigger element 102 which actually engages the tripping element 108 is approximately parallel to the plane of the adjacent edge of the door, especially when the trigger is in the tripped position shown in this figure. Thus, when the door swings shut, the trigger element wipes its cam face along the end of the screw 108 instead of bringing up solidly against the side of the screw 108. For this reason, the door can move past its normal closed position without bending or otherwise injuring the trigger 102 or any of the mechanism associated therewith. Hence it is not necessary that the inner edge of the door bear strongly against the usual rubber pad or buffer 109 which is mounted on the jamb, when the door is in its closed position. Ordinarily such a buffer serves both to cushion the impact of the door when it is slammed shut and also to press the shut door firmly against the latch to prevent rattling. For this reason, the buffer in the usual car must be compressed when the door is shut, necessitating a strong push or slam to shut the door. Since in the present invention the bolt 30 in the lined socket 36 serves to prevent rattling, it is not necessary for the door to press firmly against the buffer 109 when shut. On the contrary, the door may be slightly spaced from the buffer 109, when shut, or the buffer may be made of softer material than that customarily employed, so that the door can be shut by a gentle push instead of a slam. This is made possible by the form of the trigger which trips the latch when the bolt is opposite the socket 36, but which permits the door to move past its normal closed position without injury to the trigger or any other element of the mechanism.

Figures 8 to 11 inclusive illustrate a modified form of the invention in which the bolt head 30 is secured to or integral with a flat elongated shank 110 notched to receive a tumbler 112 which preferably has two or more shoulders 114 and 116 either of which is adapted to engage a lug 118 on the stationary housing wall member 120 to lock the bolt in a projected position. If, when the door has been shut, the bolt fails to be projected to its fullest extent by the operating spring, the lug 118 may catch on the shoulder 114. If, however, the bolt is projected to its extreme position, the end shoulder 116 engages the lug 118 to lock the bolt in its fully projected position. A suitable spring 122 bears against a laterally projecting portion 124 of the member 112, causing this member to tend to assume its locking position as shown in Figure 10. Operating means for retracting the bolt are located in the narrow housing defined by the wall 120 and a parallel wall 125 which is preferably integral with the end wall through which the bolt

head projects. The thickness of the housing is less than half of the width of the end wall so as to provide space for the window glass in the door. The bolt head, however, preferably has a diameter nearly as great as the width of the end wall so as to have a large bearing surface in the socket in the door jamb which it enters. The operating means may include a lever arm 126 loosely mounted on a shaft 128, this lever arm having a curved edge portion 130 bearing against the projecting portion 124 of the tumbler 112. The lever 126 is provided with an ear 132 engaged by a lug 134 on a roll-back member 136 which is fixed on the shaft 128. A spring 138 presses an arm 140 projecting from the roll-back 136, tending to turn the shaft 128 in clockwise direction, as shown in Figure 8, so as to hold the arm 140 resiliently against a stop pin 142. If the shaft 128 is rocked against the force of the spring 138, the lug 134 bears against the ear 132 so as to rock the arm 126. This presses against the projecting portion 124 of the tumbler 112 so as to move the shoulder 116 clear of the lug 118, thus releasing the bolt for retractive movement. Further movement of the arm 126 causes the bolt to be retracted with the tumbler 112 against the pressure of the spring 122 until the bolt is locked in its retracted position by another tumbler shown in Figure 9. This comprises a dog 144 which is provided with a lug 146 seated in a slot in the casing to act as a fulcrum. The dog is rocked by a trigger element 148 which projects through an opening in the end wall of the casing so as to engage a setscrew or other tripping element mounted on the door jamb. The dog 144 has an inclined edge 150 which is adapted to engage an edge portion 152 of the lever arm 126 when the latter is rocked to move the bolt in its fully retracted position. The dog 144 is pressed toward its locking position by suitable means such as a spring 154. Thus, when the lever 126 is rocked so that it clears the dog 144, the latter moves into the same plane as the lever 126 and the edge 150 engages the edge portion 152 to prevent reverse movement of the lever arm 126 until the dog 144 is rocked in the opposite direction by engagement of its trigger 148 with a tripping element on the door jamb.

The bolt 30 may be operated by an interior door handle which is connected to a sliding plate 160. This plate is provided with an ear 162 adapted to engage a corresponding ear 164 on the bolt 30 when the slide 160 is moved toward the right as in Figure 8. When the bolt is operated by rocking the shaft 128, the ear 164 simply moves away from the ear 162. The slide 160 can be moved toward the left from the position shown in Figure 8 so as to lock the bolt 30 in its projected position and to render the exterior door handle inoperative. To this end, the slide 160 is provided with an end edge portion 166 which is adapted to engage a lug 168 on the lever arm 126 when the slide 160 is moved toward the left from the position shown in Figure 8. As indicated in Figure 9, the lug 168 is provided with a sloping cam surface on which the edge of the slide 160 rides, the result being to push the upper portion of the lever arm 126 laterally against the force of a light spring 169 so that the ear 132 is disengaged from the lug 134 on the roll-back, as indicated in dotted lines in Figure 11. Since the arm 126 is loosely mounted on the circular shaft 128, manipulation of the handle attached to the shaft 128 thereupon has no effect on the lever arm 126. The slide 160 may be 75

releasably retained in the position shown in Figure 8 or in its locking position by any suitable means such as a leaf spring 170 having an end portion engaging in one or another of a pair of apertures or recesses 172 and 174 in the slide 160. The slide 160 is pressed toward the left by a suitable spring 176 which bears against a lug 178 projecting from a side face of the slide, this spring being of insufficient strength to move the slide to its locking position against the retentive force of the detent member 170. To avoid looseness or rattling of the bolt when the door is closed, the forward portion 180 of the shank is relatively thick and is slotted, as indicated in Figure 11, near the upper and lower edges to form horizontal strips 182 and 184 which project rearwardly beyond the portion 180 of the shank. A pair of short flanges or rails 185 and 186 projecting from the side wall 125 fit in the slots, providing ample bearing surface for the sliding shank of the bolt. The free portions of the strips 182 and 184 converge slightly so that, when the bolt is projected, these converging portions bind somewhat on the rails 185 and 186 and thus prevent up and down looseness of the bolt. Sidewise looseness is prevented by the engagement of the leading end edge of the shank portion 180 of the bolt with the curved corner surface of the housing wall 125 at 188 (Figure 10). This wedges the bolt head sidewise against the opposite edge of the aperture when the bolt is fully projected.

Figures 12, 13 and 14 illustrate another form of the invention in which the bolt 30 is provided with a tumbler 190 which is pivoted to the bolt as at 192. One arm 194 of the tumbler 190 engages a suitable shoulder 196 when the bolt is in projected position to lock the bolt positively against rotation. The other arm 198 projects upward and is pressed toward locking position by a suitable spring 200. The arm 198 is also engaged by an arm 202 projecting from a clutch member 204 which is slidable on a square rock-shaft 206 but which is rockable thereby. Loosely mounted on the shaft 206 is a complementary clutch member 208 which is provided with an arm 210 connected through a suitable link 212 to the interior door handle of the automobile, the shaft 206 having the exterior door handle 24 mounted thereon. A suitable spring 214 presses the clutch members 204 and 208 into engagement. Rocking movement of the shaft 206 in a counter-clockwise direction, as shown in Figure 12, presses the arm 202 against the arm 198, rocking the member 190 so as to move the arm 194 clear from the shoulder 196. Further movement of the arm 202 pushes the bolt 30 to its retracted position against the pressure of the spring 200. Since the clutch members 204 and 208 are normally in engagement as indicated in Figure 14, the arm 202 may also be rocked by manipulation of the interior door handle. Operation of the interior door handle in the opposite direction, however, causes the inclined edges 216 of the clutch member 208 to ride upon the corresponding inclined edges 218 of the clutch member 204 causing the latter to shift along the shaft 206 against the spring 214 so that the arm 202 is moved out of connection with the arm 198. As long as the clutch member 204 is held in this laterally shifted position, manipulation of the exterior door handle 24 does not operate the bolt 30.

When the bolt is in its fully retracted position, it is locked in such position by a tumbler 220

which rocks on a fulcrum 222, this tumbler having a trigger member 224 which projects from the edge of the door to engage a tripping element such as the setscrew 108 shown in Figure 3. The end 226 of the tumbler 220 engages the arm 198 when the bolt is in its fully retracted position, as indicated in Figure 13, preventing any movement of the bolt toward the left. When the trigger member 224 is pressed against the force of a spring 228 to rock the tumbler 220 so that its end moves clear of the arm 198, the bolt can then be projected by the spring 200.

It is evident that various modifications and changes may be made in the embodiments of the invention herein shown and described without departing from the spirit or scope thereof as defined in the following claims.

I claim:

1. In a latching mechanism, a slidable bolt having a shank portion in the form of a flat plate with a circular notch in an edge thereof forming a socket, a tumbler slidable with said bolt, said tumbler having a flat circular portion fitted into said socket and rockable therein about its center, a fixed element having a shoulder engageable by a portion of said tumbler when said bolt is projected to lock said bolt in projected position, and a spring pressing against said tumbler and tending to rock said tumbler to its shoulder-engaging position and push said bolt to its projected position.

2. In a latch mechanism, a longitudinally slid able bolt having a shank portion with a circular recess in a side thereof forming a socket, a tumbler rockably mounted on said bolt to slide therewith, said tumbler having a circular portion fitted within said recess and a pair of arms projecting in different directions from said circular portion, a spring pressing against one of said arms in a direction to push said bolt forward toward its projected position, and a fixed member normally engaged by the other arm of said tumbler to pre-

vent rocking movement of the tumbler by said spring, said fixed member having a shoulder engageable by said other arm when the bolt is projected and the tumbler is rocked by the spring

5 to lock the bolt against retraction.

3. In a latch mechanism, a longitudinally slid able bolt, a tumbler pivoted to said bolt for limited rocking movement relative thereto, said tumbler being in the form of a bell-crank with one arm extending upward and the other arm extending rearward, a spring pressing against the upward arm tending to rock said tumbler forward and to push said bolt forward, and a fixed member having a horizontal surface engaged from below by said rearward arm to prevent rocking of said tumbler until the bolt is projected, said fixed member also having a shoulder engageable by said rearward arm to prevent retraction of said bolt.

20 4. In a latch mechanism, a longitudinally slid able bolt having a shank portion in the form of a plate with a circular notch in an edge thereof forming a socket, a member having a circular portion fitted into said socket whereby said member is rockable through a limited angle relatively to said bolt, and operating means engaging said member to slide said bolt and rock said member.

25 5. In a latching mechanism, a housing, a bolt having a shank slid able in said housing, a tumbler mounted on said shank to rock about a stationary pivot thereon, a spring mounted in said casing and pressing forwardly against said tumbler at a point vertically offset from said pivot whereby said spring tends to rock said tumbler and to project said bolt, and a fixed member engaged by said tumbler to prevent rocking movement of the tumbler by said spring, said fixed member having a shoulder engageable by said tumbler when the bolt is projected and the tumbler is rocked to lock the bolt against retraction.

SIDNEY B. WHITTIER.
